CLAIM

The ornamental design for a children's electric motorcycle, as shown and described.

DESCRIPTION

FIG. 1 is a top, front, and left side perspective view of a children's electric motorcycle embodying my new design; FIG. 2 is a bottom, rear, and right side perspective view thereof;

FIG. 3 is a left side elevation view thereof;

FIG. 4 is a right side elevation view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is an enlarged and partial perspective view of area 9 in FIG. 1;

FIG. 10 is an enlarged and partial perspective view of area 10 in FIG. 2;

FIG. 11 is an enlarged and partial perspective view of area 11 in FIG. 2;

FIG. 12 is an enlarged and partial left side elevation view of area 12 in FIG. 3; and,

FIG. 13 is an enlarged and partial right side elevation view of area 13 in FIG. 4.

The dashed broken lines in the figures are for the purposes of illustrating portions of the children's electric motorcycle, which form no part of the claimed design.
